UNITED STATES PATENT OFFICE.

HENRY A. KIESELHORST, OF ST. LOUIS, MISSOURI.

SAFETY-RAZOR.

956,532.

Specification of Letters Patent.

Patented May 3, 1910.

Application filed January 2, 1909. Serial No. 470,521.

To all whom it may concern:

Be it known that I, HENRY A. KIESELHORST, a citizen of the United States, and resident of St. Louis, Missouri, have invented certain new and useful Improvements in Safety-Razors, of which the following is a specification containing a full, clear, and exact description, reference being had to the accompanying drawings, forming a part hereof.

My invention relates to a safety razor, the object of my invention being to provide a simple holder adapted to receive a thin narrow blade having a cutting edge and which 15 blade is clamped between the edges of a pair of plates, one of which is rigid and the other flexible, and the cutting edge of the blade to be positioned adjacent a guard formed on the lower end of the head of the holder.

20 A further object of my invention is to construct a safety razor wherein very thin narrow blades can be utilized, thus materially reducing the cost of manufacture of said blades and consequently reducing the cost of 25 the blades to the user.

In nearly all forms of safety razors now in general use a comparatively wide blade is made use of, and which form of blade contains considerable material which is wasted 30 when the blades are thrown away after having become dull. I propose to form a blade from a very thin and narrow piece of plain sheet steel, devoid of lugs, notches or apertures, and which is only of such size as to 35 have sufficient body to be gripped between a pair of plates.

In practice I have demonstrated that practical blades can be formed of sheet metal having a thickness of approximately three 40 one-thousandths of an inch, an inch and a half in length, and one-eighth of an inch in width, and thus it will be readily seen that the blades can be very cheaply produced, as compared to safety razor blades of the present construction.

To the above purposes, my invention consists in certain novel features of construction and arrangement of parts hereinafter described, claimed and shown in the accompanying drawings, in which:

Figure 1 is an elevation of a safety razor of my improved construction; Fig. 2 is an end elevation looking at the head of the razor; Fig. 3 is an enlarged vertical section 55 taken longitudinally through the center of

a razor of my improved construction; Fig. 4 is a vertical section taken through the head of the razor and showing the plates swung into open positions; Fig. 5 is a vertical section taken on the line 5—5 of Fig. 4; Fig. 6 60 is a cross section taken on the line 6—6 of Fig. 3; Fig. 7 is an elevation of a sheet of metal from which razor blades are formed; Fig. 8 is an elevation of a narrow strip of material from which the razor blades may be 65 formed; Fig. 9 is a plan view of a guard or packing strip on which the razor blades are packed; and Fig. 10 is an enlarged cross section taken on the line 10—10 of Fig. 9.

Referring by numerals to the accompanying drawings; 1 designates the handle of the holder of my improved razor, which handle is in tubular form and provided at one end with a head 2, in the form of a transversely curved plate, the lower edge of which is provided with a series of teeth 3, which form a guard to prevent the razor blade from cutting the skin while the razor is in use. Formed in the face of the plate 2, immediately above the teeth 3, is a longitudinally 70 disposed shallow groove 4.

Hinged to the top of the plate 2, is a blade holding plate 5, which is curved transversely to conform to the curvature of the plate 2, and said plate 5 is of such thickness as that 85 it is perfectly rigid; and formed in the inner face of this plate 5, and at the free edge thereof, is a continuous groove 6, which receives the narrow razor blade hereinafter described. The plate 5 is of such width as 90 that this groove 6 occupies a position directly opposite the shallow groove 4 when the plate 5 is swung downward in front of said plate 2.

Seated in the lower portion of the plate 95 5, and in the wall immediately in front of the groove 6, is a series of disks 7, of soft iron, which perform the function of armatures in order that the razor blades, which are magnetized, will be held in the groove 100 6 by magnetism when seated therein, thus preventing the blades from dropping from the holder when the parts are being assembled and adjusted for use.

Formed integral with the central portion 105 of the plate 5, and projecting inward therefrom, is a lug 8, in which is formed a notch 9, the inner end of which is extended laterally at right angles as designated by 10.

Hinged to the upper end of the plate 2, 110

between said plate and the plate 5, is the upper end of a thin flexible plate 11, in the center of which is formed an opening 12, and formed on this plate adjacent its free edge is a longitudinally disposed rib 13, which when the razor is assembled for use occupies the position in the shallow groove 4, thus maintaining said plate 11 rigidly between the plates 5 and 11.

10 The blades 14 utilized in my improved razor are formed from a thin sheet of steel and said blades being equal in length to the length of the plates 2, 5 and 11, and of such width as to occupy and fill the groove 6, and 15 the sharpened edge of said blade projecting beyond the edges of the plates 5 and 11 and occupying a position immediately in front of the teeth 3 forming the guard.

10 The means utilized for clamping the plates 5 and 11 together and maintaining the same against the curved plate 2, comprises a rod 15, the forward end of which is provided with a pair of oppositely arranged lugs 16, which are adapted to enter the notch 9 and 25 pass into the laterally disposed ends 10 thereof when the parts of the razor are assembled, and formed integral with the rear end of this rod 15 is a screw threaded head 17 which is adapted to receive a cylindrical 30 nut 18.

In Fig. 7 I have shown the thin narrow blades as being formed from a plate of sheet steel and where this arrangement is carried out one edge of the metal plate is ground 35 and sharpened, after which the material at the end of the plate is cut off on a transverse line to form the narrow blade.

The blades are magnetized either before or after manufacture, in order that they 40 will, by the action of magnetism, adhere to the soft metal disks 7 when positioned in the groove 6, and thus said blades are held in said groove until the plates 5 and 11 are drawn together to rigidly clamp the blade.

45 In Fig. 8 I have shown the blades as being formed from a narrow ribbon or tape, one edge of which is sharpened, after which said ribbon or tape is separated into suitable lengths to form the blades. It is the intention that the blades utilized in my improved 50 razor are to be formed and sharpened by specially designed machinery, and for this reason and the fact that very little material is required for said blades, the same can 55 be very easily and cheaply produced.

The blades when packed for sale and delivery are preferably located in narrow strips of corrugated paper as seen in Figs. 9 and 10, and in order to maintain the blades 60 on said strip of paper said blades and paper are immersed in suitable liquid, such as paraffin, which causes the blades to adhere to the paper and also protects said blades against the action of rust due to the presence 65 of moisture. This coating of paraffin, or

the like, is extremely thin and in nowise affects the cutting action of the blades while in use.

When a blade is to be inserted in the holder for use, the forward end of the rod 13 is disengaged from the notches 10 in the lug 8, and the plates 5 and 11 are now free to swing outward away from the plate 2, as shown in Fig. 4. One of the thin narrow blades is now positioned in the groove 6, and said blade is held therein by magnetic action between said blade and the disks 7, and the thin resilient plate 11 is now swung against the plate 5, or in such a position as that the free edge of said plate 11 bears against the under side of the blade seated in the groove 6. Both plates 5 and 11 are now swung downward onto the plate 2, and thus the lug 8 is moved into a position within the forward end of the handle 1. The forward 70 end of the rod 15 is now inserted in the notch 9 in the lug 8, after which said rod is slightly rotated to cause the lugs 16 to enter the notches 10, and the nut 18 is now manipulated on the threaded head 17 in such a manner as 75 to tighten against the end of the handle 1, and consequently draw the plates 5 and 11 80 tightly against the plate 2, which action 85 rigidly grips the blade 14 held between the edges of said plates 5 and 11.

A razor of my improved construction is very simple and inexpensive, can be easily assembled, taken apart and cleaned, and utilizes blades which can be very easily and cheaply produced.

I claim:

1. In a safety razor, the combination with a head, guard teeth carried by said head, a pair of clamping plates hinged to said head, one of which plates is flexible, of a thin, narrow blade adapted to be clamped between the free edges of said plates.

2. In a safety razor, the combination with a head, guard teeth on said head, a pair of clamping plates hinged to said head, one of which plates is flexible, of a thin, narrow blade arranged between the free edges of said plates and means whereby said plates are clamped together to grip the blade.

3. In a safety razor of the class described, a curved head therefor guard teeth on said head, a rigid plate hinged to one side of the head, a flexible plate hinged to the head and occupying a position between said head and the hinged plate, whereby a thin narrow 120 blade may be detachably arranged between the free edges of the flexible plate and the hinged plate.

4. In a safety razor of the class described, a holder, a curved head therefor guard teeth 125 on said head, a rigid plate hinged to one side of the head, a flexible plate hinged to the head and occupying a position between said head and the hinged plate, a thin narrow blade detachably arranged between the free 130

edges of the flexible plate and the hinged plate, and means whereby the flexible plate and the hinged plate are rigidly held against the head of the holder.

5. A safety razor, comprising a curved plate, a series of guard teeth on one edge of said plate, a pair of plates hinged to the opposite edge of the curved plate, one of which pair of plates is flexible, and a thin 10 narrow blade detachably held between the free edges of the pair of hinged plates.

6. A safety razor, comprising a curved plate, a series of guard teeth on one edge of said plate, a pair of plates hinged to the 15 opposite edge of the curved plate, one of which pair of plates is flexible, a thin narrow blade detachably held between the free edges of the pair of hinged plates, and means whereby said pair of plates are caused to 20 grip the blade and to rigidly engage against the curved plate on the holder.

7. In a safety razor, the combination with a head, guard teeth on said head, a pair of clamping plates hinged to said head, of a 25 magnetized blade positioned between the free edges of said plates and means for clamping the plates to hold the blade.

8. In a safety razor, the combination with a head, guard teeth on said head, a pair of

clamping plates hinged to said head, one of 30 which plates is flexible, of a magnetized blade positioned between the free edges of said plates armatures carried by one of said plates and means for clamping the plates to hold the blade.

35 9. In a razor of the class described, a holder, a pair of gripping plates hinged thereto, a soft metal plug inserted in one of the gripping plates, a magnetized razor blade adapted to be positioned between the 40 gripping plates adjacent the soft metal plug, and means whereby the plates are caused to grip the razor blade and to rigidly bear against the holder.

10. In a safety razor, the combination of 45 a head, guard teeth on said head, a non-flexible clamping plate hinged to said head, a flexible plate and a blade positioned between the edges of said plates and means for clamping the plates to hold the blade. 50

In testimony whereof, I have signed my name to this specification, in presence of two subscribing witnesses.

HENRY A. KIESELHORST.
